W. J. GOUDÉAU

COIN CONTROLLED LOCK FOR CARRIERS

Filed April 9, 1921

Wilton J. Goudeau,

By *Watson E. Coleman*
Attorney

UNITED STATES PATENT OFFICE.

WILTON J. GOUDEAU, OF GRIDER, ARKANSAS.

COIN-CONTROLLED LOCK FOR CARRIERS.

Application filed April 9, 1921. Serial No. 459,878.

To all whom it may concern:

Be it known that I, WILTON J. GOUDEAU, a citizen of the United States, residing at Grider, in the county of Mississippi and 5 State of Arkansas, have invented certain new and useful Improvements in Coin-Controlled Locks for Carriers, of which the following is a specification, reference being had to the accompanying drawings.

10 This invention relates to vending systems or self-serving store systems of that character in which carriers or baskets operable on endless conveyors are shifted by the buyer until the proper basket is exposed, the basket or 15 carrier then being opened by the insertion of a coin.

One of the objects of the present invention is to provide a coin controlled lock particularly adapted to be used in connection 20 with baskets or carriers of the character above stated, which is particularly convenient and simple, and in which the cover of the basket or carrier is held closed by a hasp released upon the introduction of a coin.

25 Other purposes have to do with the details of construction and arrangement of parts as will appear more fully hereinafter.

While the design and construction at present illustrated and set forth is deemed preferable, it is obvious that as a result of a reduction of the invention to a more practical form for commercial purposes, the invention 30 may be susceptible of changes, and the right to these changes is claimed, provided they 35 are comprehended within the scope of what is claimed.

The invention comprises further features and combination of parts, as will be herein-after set forth, shown in the drawings and 40 claimed.

In the drawings:—

45 Figure 1 is a vertical sectional view showing the casing of a vending machine, and showing the endless conveyor or chain, with the baskets mounted thereon.

50 Figure 2 is an enlarged detail view of the brake mechanism for the lower shaft of the conveyor, to permit the shaft and the conveyor from being operated too rapidly.

55 Figure 3 is an enlarged view in side elevation of one of the baskets or carriers as mounted on the conveyor, showing one corner of the basket broken away, in order to show the lock between the slide or plunger and the cover.

Figure 4 is an enlarged detail sectional view through the coin controlled lock.

Figure 5 is an enlarged detail perspective view of the coin controlled lock.

Figure 6 is a view in front elevation of 60 the upper part of the basket showing the lock mechanism.

Referring to the drawings, 1 designates a casing, which may be any suitable construction or contour, and constructed of any suitable material. Mounted in bearings of the upper part in the casing is a shaft 2 having a sprocket wheel 3, and mounted in the lower part is a shaft 4 having a crank 5, there being a suitable brake 6 for preventing the 70 shaft from being rotated too rapidly. This brake comprises a band bent upon itself to provide opposing arms 7, this band being attached to the casing, as at 8. The arms 7 are formed to provide circular gripping 75 jaws 9, the bent terminals 10 of which receive a screw 11 provided with a thumb nut 12. By tightening up on the thumb nut, the semi-circular jaws 9 may be actuated to bear frictionally on the periphery of a disc 80 13 fixed to the shaft 4, thereby acting to retard the action of the shaft. The casing 1 has a door *a* hinged at *b*, for closing the opening *d*, there being a suitable latch *g* to hold the door closed.

85 A sprocket *h* is carried by the shaft 4, and engaging about the sprocket *h* and the sprocket 3 is an endless conveyor or chain *k*, to which is connected at intervals baskets or carriers *m*, in which the articles to be purchased are located. Each basket (which is 90 constructed of a heavy wire frame *n*, with mesh work bottom, sides and end pieces *q*) has a cover or closure *w*, which is hinged at *p*, and is provided with a keeper *z*.

95 Secured in any suitable manner as at 14 to the side of the basket or carrier is a casing 15 of a coin controlled lock. This lock (which is similar to that described and illustrated in the copending application of Wilton J. Goudeau, for vending machines for grocery commodities, filed September 18, 1920, Serial No. 411,185) has its housing or casing provided with a guide 18 for the reception of the shank 19 of a hasp or locking bar.

100 In order to provide a guide 18, the upright portion of the housing or casing of the coin controlled lock has an inner body 20 disposed on the bottom of the housing. The coin chute 22 is mounted upon the casing or 105 110

housing 20 and has a coin passage 23. This passage extends through the body 20 so as to permit of the passage of the coin 24. The bottom 25 of the passage is inclined, so as to cause the coin 24 to roll toward the chute 26. One of the side walls of the coin passage is provided with a ledge 28 having a pair of stops 29 and 30. The side wall of the lateral portion of the coin passage 23 has an additional ledge or shoulder 31, which acts to guide the shank 19 of the hasp, and pivoted on one side of the hasp shank 19 as at 32 is a dog 33 provided with a beveled end 34. The end of the dog 33, when the hasp shank 19 is in a reseated or normal position, engages the stop shoulder 29 and prevents the hasp shank 19 from being actuated. Fastened securely at 35 on one side of the dog and positioned directly above the incline 25 is a coin engaged guide 36. This guide 36 is inclined relatively to the side of the hasp shank 19 and to the incline 25, so that when the coin travels down the inclination 25, it will become positioned under the coin guide 36 and act to raise the dog upwardly permitting the shank 19 of the hasp to be pulled outward. A light coiled spring 37 is connected to the rear portion of the hasp shank 19 as at 38, and in turn is connected to one of the screws 35, thereby acting to hold the dog normally in engagement with the stop shoulder 29.

The shank 19 has a lateral portion 39 terminating in an arm 40, which is parallel to shank 19. The shank 19 operates through an opening 41 in the front wall of the basket or carrier, while the arm 40 operates through an opening 42, so that its terminal may engage with the notch 43 of the keeper 2, thereby holding the cover or closure in a closed position. The coin chute 26 connects at 44 with a conventional form of coin box 45, which is fastened in any suitable manner as at 46 to the side of the basket, carrier, or receptacle.

Obviously when a coin is inserted through the coin chute, it rolls down the incline 25, and engages under the coin guide 36, thereby raising the dog 33 from contact with the shoulder or stop 29, in which case the pull lever 19 is free to be withdrawn, and when withdrawn, the coin will roll into the chute 26, and thence into the coin box. When the pull lever is withdrawn, the terminal of the arm 40 disengages from the notch of the keeper, thereby releasing the cover, which may be lifted, to permit the purchaser to remove the desired article.

While simply a plain hinge door or closure α is employed in connection with the casing 1, it is obvious that a mechanism such as shown in the application filed September 18, 1920, Serial No. 411,185, for actuating the endless conveyor may be used in connection with the door or closure, so that when

the door or closure is opened the endless conveyor may be operated. Also it is obvious that a second coin controlled lock may be used in connection with the door α , so that when a pull bar such as 19 is withdrawn, the door α may be opened, as in said application above mentioned. Furthermore it is to be understood that while this coin controlled lock is designed for use in connection with a vending machine for vending grocery commodities, it is obvious that the coin controlled lock may be applied to a vending machine for vending any articles.

The invention having been set forth, what is claimed as being useful is:

1. In a check controlled lock for containers, the combination with a container including a cover therefor having a keeper, a lock casing carried by the container including a guide, a locking member mounted in the guide of the casing and provided with a return bent arm engaging the keeper of the cover, the interior of the lock casing having an abutment, a gravity member carried by the locking member engageable with the abutment to lock the return bent arm in engagement with the keeper, and a device carried by the gravity member to be engaged by a check to raise the member out of engagement with the abutment to permit the locking member to be actuated to release the cover.

2. In a check controlled lock for containers, the combination with a container including a cover having a keeper, of a lock casing connected to the wall of the container and provided with a guide, a locking member operable in the guide, and having means to engage said keeper, the interior of the casing having an abutment, a gravity member pivoted on the locking member and disposed in the path of and engageable with the abutment, the interior of the casing having an inclined guide, a chute on the casing, the locking member having an opening registerable with the chute to permit a check passing through the chute to drop into and roll down the inclined guide in a direction toward the gravity member, and means on the gravity member to be engaged by said check, to raise the gravity member from the path of the abutment, whereby the locking member may be withdrawn to disengage its means from the keeper.

3. In a check controlled lock for container closures, the combination with a lock casing including a chute and a locking member operable in the casing, the locking member having an opening registerable with the chute and provided with holding means, a keeper carried by the cover of a container to be engaged by the holding means, a gravity member operatively mounted on the locking member, means on the interior of

the casing to be engaged by the gravity member to retain the holding means in engagement with the keeper, a cam on said gravity member, and means on the interior 5 of the casing to guide a check to be passed through the chute into engagement with the cam to raise the gravity member out of engagement with the member engaging means to release the holding means from engagement with the keeper.

4. In a device for the purpose set forth, a check controlled lock for container closures, a keeper carried by the closure, a lock casting carried by the container and provided 15 with a passage to receive an actuating check, a locking member mounted in the casing for reciprocating movement, and provided with an opening registrable with the passage to permit of the passage of said check, 20 said locking member having an arm engageable with the keeper, tilttable means carried by the locking member to retain the arm in engagement with the keeper, means on the interior of the casing to be engaged by the 25 tilttable means of the locking member, an inclined cam carried by the tilttable means to be engaged by said check to raise the tilttable means out of engagement with the holding means which is engaged by the tilttable 30 means, whereby the locking member may be actuated.

5. As an article of manufacture, a check controlled lock for container closures, a keeper carried by the closure, a lock casting carried by the container and provided 35 with a passage to receive said check, a locking member mounted in the casing for reciprocating movement and provided with an opening registrable with the passage to 40 permit of the passage of said check, said locking member having an arm engageable with the keeper, tilttable means carried by the locking member to retain the arm in engagement with the keeper, means on the interior of the casing to be engaged by the 45 tilttable means to prevent movement of the locking member, an inclined cam carried by the tilttable means to be engaged by said check to raise the tilttable means out of engagement with the holding means which is engaged by the tilttable means, whereby 50

the locking member may be actuated, the interior of the casing having an inclined surface on which the check is guided to engage the inclined cam.

6. As an article of manufacture, a check controlled lock for container closures, a keeper carried by the closure, a lock casting carried by the container and provided with a passage to receive said check, a locking member mounted in the casing for reciprocating movement and provided with an opening registrable with the passage to permit of the passage of said check, said locking member having an arm engageable with the keeper, tilttable means carried by the locking member to retain the arm in engagement with the keeper, means on the interior of the casing to be engaged by the tilttable means to prevent movement of the locking member, an inclined cam carried by the tilttable means to be engaged by said check to raise the tilttable means out of engagement with the holding means which is engaged by the tilttable means, 75 whereby the locking member may be actuated, the interior of the casing having an inclined surface on which the check is guided to engage the inclined cam, and a guide surface on the interior of the casing 80 to be engaged by the tilttable means when the locking member is withdrawn, and means at one end of the guide surface to be engaged by the tilttable means to limit the locking member in its withdrawing movement.

7. The combination with a container including a cover having a keeper and a casing mounted on the container, of an approximately U-shaped locking hasp having one leg adapted to engage the keeper and having its other leg extending into the casing and having longitudinal movement therein sufficient to remove the first named leg from its engagement with the keeper, and means disposed within the casing and holding the hasp from movement, and coin-operated means for releasing said holding means.

In testimony whereof I hereunto affix my signature.

WILTON J. GOUDEAU.
